UNITED STATES PATENT OFFICE.

SALLIE L. DAVIS, OF LOS ANGELES, CALIFORNIA.

ADJUSTABLE STEEL OUTSIDE WINDOW-BED.

1,190,222.

Specification of Letters Patent.

Patented July 4, 1916.

Application filed August 11, 1915. Serial No. 45,022.

To all whom it may concern:

Be it known that I, SALLIE L. DAVIS, a citizen of the United States, residing at Los Angeles, in the county of Los Angeles and State of California, have invented new and useful Improvements in Adjustable Steel Outside Window-Beds, of which the following is a specification.

This invention relates to an adjustable steel outside window bed, which may be adjusted to fit any width window and made any length desired.

It is an object of this invention to provide an adjustable steel outside window bed of such a construction that by changing a few bolts the members thereof may be taken down and reassembled to form various other structures.

It is another object of my invention to provide an adjustable steel outside window bed structure which may be removably fixed in a window opening with a portion of the structure outside of the building, yet securely and safely supported.

My invention comprises a structure formed of angle irons, bars, braces, rods and bolts which are conveniently bored and slotted so that the bed may be quickly and easily set up, taken down and reassembled to form other structures. The only tool required is a monkey-wrench.

An embodiment of my invention is illustrated in the accompanying drawing, in which:

Figure 1 is a perspective view of my improved adjustable steel outside window bed. Fig. 2 is a fragmentary enlarged plan view as seen on the line 2—2 of Fig. 1. Fig. 3 is a side elevation of the fragment shown in Fig. 2. Fig. 4 is an enlarged horizontal section as seen on the line 4—4 of Fig. 1. Fig. 5 is an enlarged side elevation of a foot for the window sill. Fig. 6 is a section as seen on the line 6—6 of Fig. 5. Fig. 7 is a perspective view of the elements assembled as an inside bed.

Referring more particularly to Figs. 1, 2, 3, 4, 5 and 6, side rails which are preferably of steel and of angle form are indicated at 10 and 11. 12 and 13 are end rails preferably of steel and of angle form. The rails 10, 11, 12 and 13 are bolted together to form a rectangle with the horizontally disposed leg of the angle turned inward. Secured to the end rail 12 at the

foot of the bed are steel bars 14 and 15 bent at right angles at one end as indicated at 16 and 17 to provide feet. The feet are apertured, thereby providing screw or bolt holes for securing the bars to the floor. 60 Throughout the length of the foot bars are bolt holes, and at the upper ends the bars are looped as indicated at 18 and 19. Angle braces 20 and 21 are secured by bolts to the end rail 12, and to the bars or bed legs 14 65 and 15 respectively, thereby providing a foot structure for the bed which is rigid with respect to lateral movement. Angle braces 22 and 23 are secured to the legs 14 and 15 and the side rails 10 and 11 respectively, and angle braces 48 and 49 are secured to the legs 14 and 15 and adapted to be secured to the floor thereby strengthening the bed against rocking longitudinally. A rod 24 is disposed within loops 18 and 19, thereby 70 providing means for hanging curtains or for any other convenient purpose.

Bars 25 and 26 are secured to side rails 10 and 11 respectively at points intermediate the ends of the side members and adjacent 80 the head end. The upper ends of the bars are looped in a manner similar to bars 14 and 15. Angle braces 27 and 28 are bolted to bars 25 and 26 and to side rails 10 and 11 respectively. On the opposite side of 85 bars 25 and 26 are angle braces 29 and 30 secured by bolts to side rails 10 and 11 respectively. Bars 25 and 26 form legs which are securely braced against rocking in a longitudinal direction. Bars 25 and 26 and 90 braces 27, 28, 29 and 30 are each formed with bolt holes providing convenient means for securing the members when assembled to form other structures as heretofore enumerated.

The bars or legs 25 and 26 are each provided with sill foot pieces 31 and 32. The sill foot pieces comprise similar bars 33 and 34 which are provided with laterally extending portions 35 and 36 adapted to engage 100 the sides of the window sill. The bars are also provided with longitudinal grooves 37 and 39 designed to register with one another and to receive bolts 40 and 41 for locking the bars together, thereby providing means for adjustably fixing the distance between the extensions 35 and 36 to adapt the foot to any size of window sills. The legs 25 and 26 are secured to the feet by bolts 42. The bed is secured to the window frame by dis- 110

posing the legs 25 and 26 between the beads for the sashes and attaching the leg to the frame by means of screws.

Referring particularly to Fig. 4, 44 indicates a window frame provided with beads to which the leg 26 is secured.

It will be noted that the structure as described is disposed partly within the room and partly without; the head end being outside the room. As shown in Fig. 7 four apertured cross pieces or slats 45 are bolted to the horizontal portions of the angle bars 10 and 11 and support three metallic plates 47 thereby providing a support for bedding or a floor.

The head and foot rails 12 and 13 and slats 45 are provided with holes similarly placed so as to permit the body of the bed to be adjusted to any width. The metallic plates 47 being in three sections will admit of that arrangement, as they may overlap one another and at any stage may be bolted together and to the slats 45 or the side rails of the bed 10 and 11.

If desired, flowers may be placed on the portion of the structure outside the window, and the portion within the room may be used as a table for various purposes such as playing games or dining. Where the structure is used as a bed, if desired, springs may be placed upon the metallic plates 47 and the head of the bed curtained or screened as indicated at 46'.

The members may be assembled to form an inside bed as shown in Fig. 7. Legs 25 and 26 are removed from the sides of the rectangular frame and secured to the end rail 13. Braces 22 and 23 are secured to legs 25 and 26 respectively and braces 48 and 49 to the legs 14 and 15. A rod 46 similar to rod 24 may be secured by means of loops at the upper ends of legs 25 and 26. The metallic plates indicated at 47 may then be laid across the slats 45, thereby forming a support for the bedding. An elevated platform may be constructed by attaching legs 14 and 15 at their upper ends to side member 10 and similarly legs 15 and 26 to side member 11, and braces placed below the side members.

My adjustable steel outside window bed is constructed along the lines of safety first, and is so arranged that it will be securely and safely supported within a window frame without using screws or other securing means for attaching the leg members 25 and 26 to the frame, although for the

sake of comfort for the occupant, I have provided places where the legs may be screwed to the sill and to the floor.

60

What I claim is:

1. In an adjustable outside window bed, a frame comprised of side, foot and head rails detachably secured together; slats disposed on said frame; supporting legs detachably secured to said frame at the foot thereof; braces, one detachably secured to each of said feet and to the foot rail; angle braces, one detachably secured to each of said feet and its corresponding side rail; angle braces, one detachably secured to each leg and adapted to be secured to the floor; legs detachably secured to said side rails at points spaced from the head end of said frame; angle braces, one detachably secured to each of the last mentioned legs and to the corresponding side rails; angle braces, one secured to each of the last mentioned legs and to the corresponding side rail on the side of the leg opposite to the last mentioned angle braces; and sill foot pieces detachably secured to the legs at the head end of the bed, said foot pieces comprising bars slotted longitudinally and provided with laterally extending portions at one end adapted to engage the sides of the window sill for locking the bed to the window sill.

2. In an adjustable outside window bed, a frame comprised of side, foot and head rails detachably secured together; slats disposed on said frame; supporting legs detachably secured to said frame at the foot thereof; braces, one detachably secured to each of said feet and to the foot rail; angle braces, one detachably secured to each of said feet and its corresponding side rail; angle braces, one detachably secured to each leg and adapted to be secured to the floor; legs detachably secured to said side rails at points spaced from the head end of said frame; angle braces, one detachably secured to each of the last mentioned legs and to the corresponding side rails; angle braces, one secured to each of the last mentioned legs and to the corresponding side rail on the side of the leg opposite to the last mentioned angle braces; foot pieces detachably secured to the legs at the head end of the bed having fingers adapted to engage the sides of the window sill.

In witness that I claim the foregoing I have hereunto subscribed my name this 27th day of July, 1915.
